UNITED STATES PATENT OFFICE

WILLIAM McDONALD, OF CHICAGO, ILLINOIS, ASSIGNOR TO SWIFT & COMPANY, OF CHICAGO, ILLINOIS, A CORPORATION OF ILLINOIS

CONTINUOUS SCREW PRESS

Application filed October 1, 1926. Serial No. 138,885.

My invention relates to improvements in a type of screw presses used in various arts for the purpose of expressing the liquid constituents of the material acted upon, and the particular embodiment of my invention hereinafter particularly described is designed and adapted to separate oil and grease from cooked cracklings consisting of meat trimmings, boney and gristly portions of meat, condemned carcasses and miscellaneous similar packing house offal.

In the packing industry, it is usual, in utilizing such portions of meat carcasses, to cook the material in steam jacketed vessels, whereby the moisture is driven off from the solids and the grease cells broken down. In the case of materials having a high grease content, the free grease may be drawn off during the cooking operation, or drained off from the cooked cracklings, at its conclusion. There remains a considerable quantity of grease, however, adherent to and contained in the solid cracklings, which cannot be thus removed, and in some cases hydraulic presses, and in others continuous screw presses of the type to which my invention relates, have been used, but the amount of grease remaining in the solid portions is greater than desirable for best utilization of the solids. The solids contain a large proportion of protein, besides the residue of grease, and, when dried and ground form a nutritious and valuable stock food. Too large a proportion of fat in the product, however, is detrimental to the development of poultry, as well as producing a sales loss in produce.

It is therefore, important to express as much of the grease as possible from the cooked material, and the object of my invention, stated generally, is the improvement of screw presses to obtain a more complete separation of the liquids and solids, whereby I obtain an increased yield of fat, and also a more desirable residue of the solid materials. To this end I have devised an improved construction of the feed chamber at this point where the material enters the compression chamber of the machine, whereby bridging of material passing through the feed chamber is avoided and the formation of voids in

the stream of material is avoided, and whereby, also, the material is partly compressed before entering the compression chamber; and I have also devised an improved construction of the worm extending through the feed and compression chambers, which acts to break down bones and solid pieces of material, and further serves to prevent bridging of the material and the formation of voids, the form of the feed chamber and action of the screw thus causing an even feed and flow of material and uniform and increased pressure in the compression chamber which results in increased efficiency in action of the machine.

In the drawings, Figure 1 is a top plan view of my improved continuous screw press; Fig. 2 is a side view of the same; Fig. 3 is a horizontal section of the central portion of the machine taken in a plane extending axially of the compression chamber and on a larger scale than Figs. 1 and 2; Fig. 4 is a vertical cross-section in a plane indicated by the dotted line 4-4 of Fig. 1 and on the same scale as Fig. 3; Fig. 5 is a central vertical section of the portion of the machine adjacent the feed end of the feed screw and also on the same scale as Fig. 3; Fig. 6 is a vertical cross-section through the compression chamber in a plane indicated by the dotted line 6-6 of Fig. 5; Fig. 7 is an enlarged fragmental cross-section of a portion of the compression chamber, and Fig. 8 is a detail of the same parts, partly in section, as indicated by the dotted lines 8-8 of Fig. 7.

Like reference characters indicate like parts on all the figures of the drawings.

Describing briefly the machine illustrated in the drawings and in which my invention is embodied, the frame work which may be variously constructed, preferably consists of metal members X rigidly bolted or otherwise secured together and arranged to suitably support the moving and stationary elements of the machine. The crackling hopper 1, in the bottom of which is arranged a worm 2, is arranged to deliver the cracklings through a chute 3 to one end of a steam-jacketed drum 4 in which is arranged a helical conveyor 5.

arranged to convey the material to a feed chute 6 which at its lower end communicates with the feed chamber 7 adjacent the feed end of the feed screw 8. An inclined spiral feeding worm 9 extends downwardly in said feed chute to the upper front or entrance side of the feed chamber. The wall of this feed chamber (see Figs. 3, 4 and 5) is contiguous to the feed screw 8 along its bottom, and 5 spreads laterally from rear to front below the bottom of and in the path of the material delivered by said spiral feeding worm 9, which is an important feature of my invention, as will be hereinafter explained. The 10 rear side of the feed chamber opens into the pressure barrel or compression chamber of the machine, which in the present instance is of built-up construction and for the purpose of complete exposition may here briefly be 15 described. The barrel frame includes a pair of upper bars 10, bolted to frame members 11, between which are clamped, by means of bearing clamping bolts 12, a series of spaced retaining blocks 13 arranged between the 20 bolts. The blocks 13, which are arranged in pairs have semi-cylindrical inner faces and are secured together in spaced relation by means of spacing bars 14 let into the upper bars and 14^a let into the meeting faces of 25 the lower bars. The bars 14 and 14^a extend radially inward beyond the curved faces of the blocks 13 and themselves have curved inner faces which form part of the pressure barrel. Between the side faces of the bars 30 14—14^a and an upper clamping bar 15 and a lower clamping bar 16 are arranged a series of slats 17 extending edgewise from the curved faces of the blocks 13 radially of the barrel structure, these slats together constituting the larger part of the pressure barrel. The upper and lower clamping bars 15 and 16, before mentioned, have wedge-shaped side faces adapted to cooperate with the adjacent slats 17 in such manner that when the 35 bars are drawn outwardly by clamping bolts 18 having a bearing on longitudinal bars 19 bearing on the upper and lower blocks 13, the slats will be squeezed in four groups between the bars 14 and 14^a, and the bars 15 and 16.

As illustrated in Figs. 7 and 8, the side faces of the slats 17 are cut back to leave a side flange 17^a, and this flange is formed with minute semi-conical notches 20 which constitute the orifices for escape of grease from the material pressed within the barrel. The slats are held in radial alignment by spacing rings 21 let into selected blocks 13 at intervals, and notched on their inner faces to engage the outer edges of the slats.

Within the pressure barrel are arranged in axial alignment the principal screw members of the press, consisting of the feed screw 8 before mentioned and the pressure screw 22, 45 the former being arranged to rotate at a

higher speed than the latter and a suitable ratio being 3½ to 1. The pressure screw is keyed to a long main shaft 24 journaled in the frame work of the machine, and the feed screw 8 is mounted on a sleeve 21, rotatably mounted on said main shaft. As usual, the central body of the pressure screw 22 is tapered so that the spiral passage between the thread is constricted towards the rear, and at the rear end of the press the annular outlet orifices for the pressed material is 50 yieldingly obstructed by an annular spring-pressed retarding block 23 having feathered connection with the main shaft 24 to which the pressure screw 22 is fixed, so that it rotates with the latter. A thrust block 25, threaded on said shaft 24 and which may be rotated by a hand lever 26 pivoted on the block and having a ratchet connection therewith, provides means for varying the stress 55 on the spring 27 which tensions the block 23.

As illustrated in Figs. 3, 4 and 5, the front end of the feed screw 8, adjacent the front and wider side of the feed chamber and opposite the lower end of the feeding worm 9 is formed with two diametrically arranged notches which provide a pair of teeth on the screw thread at that point, this construction constituting another important feature of my invention. Two notches are shown but the 60 number is not restricted.

The operating connections for the machine may suitably include, as illustrated, a pinion A on the shaft of the electric motor used for power, meshing with a pinion B secured to a shaft to which is also secured a pinion C which meshes with a gear wheel D on a shaft D'. To the shaft D' is also secured a sprocket wheel E engaging a sprocket chain which drives a large sprocket wheel F. The latter wheel is secured to a shaft to which is also secured a pinion G engaging a large gear wheel H which is secured to the main shaft 24 before mentioned and thus rotates the pressure screw 22.

The shaft D' before mentioned also carries a pinion I meshing with a large gear wheel J secured to the sleeve 21 to which the feed screw 8 is secured.

The helical conveyor 5 is mounted on a long shaft 5^a which is driven through a sprocket wheel K on the main shaft 24 of the machine, a sprocket chain and a sprocket wheel L on said shaft 5^a. The shaft 5^a also carries a gear wheel M meshing with a pinion N on a short shaft to which is secured a bevel pinion O meshing with a bevel pinion P on the shaft to which the spiral feeding worm 9 is secured.

The worm 2 in the crackling hopper is in the present instance driven intermittently by means of a gear wheel Q on the shaft 5^a before mentioned, a small pinion R meshing therewith, a crank arm S on the shaft of said pinion, a connecting rod T pivoted to an oscillating arm U, and a ratchet on said arm ar- 130

ranged to cooperate with a ratchet wheel V which is secured to the shaft to which said worm is secured.

In the operation of the machine, the mass 5 of cracklings passing through the chute 6 is delivered into the front or larger end of the feed chamber 7 through the action of the preliminary feeding screw 9, which is rotated at such speed as to create a slight pressure in the feed chamber. This feeding worm, it will 10 be noted, is of gradually increasing diameter from top to bottom and arranged at one side of the passageway for material through the chute, a construction and arrangement which 15 in connection with the shape of the feed chamber enables the material to be fed freely through the chute and into such chamber, and because of the notches in the feed screw 8, large bones or masses or chunks of gristle or 20 other tough material delivered to the notched portion of the feed screw by the feeding worm are carried not only rearwardly into the constantly narrowing spaces at the downwardly moving side of the screw, but also down- 25 wardly as well toward the line of contact between the bottom of the feed screw and the feed chamber, with the result that such masses are broken up and fed onward between the turns of the thread of the feed screw, instead 30 of riding on the outer face of the thread, as frequently occurs in other machines of this type in which the worm is not notched. The result of the formation of voids in such other machines is a material reduction of the normal 35 pressure within the compression chamber and incomplete separation of grease from the material being acted upon. The inclined walls of the feed chamber in my improved machine, in connection with the free, unob- 40 structed flow of material into such feed chamber, causes a higher and more constant pressure to be maintained in the compression chamber than in machines not having the form of feed chamber and feed worm de- 45 scribed, and consequently results in a more nearly complete separation of the grease from the solids.

I claim:

1. A continuous screw press of the character described and having a cylindrical compression chamber and a screw member arranged to force the material operated upon therethrough, said press being formed with a feed chamber in axial alignment with the compression chamber and with a transverse feed chute opening into said feed chamber, said screw member extending into said feed chamber and being formed opposite the feed chute opening with spaced peripheral notches having a crushing action arranged to engage and break up large fragments of material entering said chamber through said opening, and the wall of said feed chamber spreading from the front end of the com-

pression chamber laterally and forwardly away from the screw member.

2. A continuous screw press of the character described and having a cylindrical compression chamber and a screw member arranged to force the material operated upon therethrough, said press being formed with a feed chamber in axial alignment with the compression chamber and with a feed chute opening transversely into said feed chamber and said screw member extending into said feed chamber, and said press having an open center feeding worm arranged at one side of the passageway through the feed chute.

3. A continuous screw press of the character described and having a cylindrical compression chamber and a screw member arranged to force the material operated upon therethrough, said press being formed with a feed chamber in axial alignment with the compression chamber and with a feed chute opening transversely into said feed chamber and said screw member extending into said feed chamber, and said press having an inclined feeding worm of gradually increasing diameter from top to bottom arranged at one side of the passageway through the feed chute.

4. A continuous screw press of the character described and having a cylindrical compression chamber and a screw member arranged to force the material operated upon therethrough, said press being formed with a feed chamber in axial alignment with the compression chamber and with a feed chute opening transversely into said feed chamber and said screw member extending into said feed chamber, and the walls of said feed chamber spreading from the front end of the compression chamber forwardly away from the screw member, and said screw press also having an inclined feeding worm arranged at one side of the passageway through the feed chute.

5. A screw press according to claim 4 in which said feeding worm is an open-center spirally-coiled member of gradually increasing diameter from top to bottom.

6. A continuous screw press of the character described and having a cylindrical compression chamber and a screw member arranged to force the material operated upon therethrough, said press being formed with a feed chamber in axial alignment with the compression chamber and with a vertical feed chute opening at its bottom into said feed chamber, said screw member extending into said feed chamber and being formed opposite the feed chute opening with spaced peripheral notches having a crushing action arranged to engage and break up large fragments of material entering said chamber through said opening, and the wall of said feed chamber spreading laterally away from said screw member from rear to front oppo-

site said feed chute opening and being contiguous along its bottom to said screw member.

7. A continuous screw press of the character described and having a cylindrical compression chamber and a screw member arranged to force the material operated upon therethrough and having also a feed chamber in axial alignment with the compression chamber and a feed chute opening transversely into said feed chamber and a spiral feeding member in said feed chute, said screw member extending into said feed chamber and being formed opposite said feeding member with spaced peripheral notches having a crushing action arranged to break up large fragments of material delivered by said feed member to the notched portion of said screw member.
8. A continuous screw press of the character described and having a cylindrical compression chamber and a screw member arranged to force the material operated upon therethrough and having also a feed chamber in axial alignment with the compression chamber and a feed chute opening transversely into said feed chamber and a spiral feeding member in said feed chute, said screw member extending into said feed chamber and being formed opposite said feeding member with spaced peripheral notches having a crushing action arranged to break up large fragments of material delivered by said feed member to the notched portion of said screw member, and the walls of said feed chamber spreading from the front end of the compression chamber forwardly away from the screw member.
9. A continuous screw press of the character described and having a cylindrical compression chamber and a screw member arranged to force the material operated upon therethrough and having also a feed chamber in axial alignment with the compression chamber and a vertical feed chute opening at its bottom into said feed chamber and a spiral feeding member in said feed chute, said screw member extending into said feed chamber and being formed opposite said feeding member with spaced peripheral notches having a crushing action arranged to break up large fragments of material delivered by said feeding member to the notched portion of said screw member, and the wall of said feed chamber spreading laterally away from said screw member from rear to front in the path of said feeding member and being contiguous along its bottom to said screw member.

In testimony whereof, I have subscribed
to my name.

WILLIAM McDONALD.
